REINFORCEMENT DEVICE

Lucius Y. Randall, Gaffney, S. C.

Application November 23, 1932
Serial No. 644,071

4 Claims. (Cl. 139—66)

This invention relates to means for reenforcing and holding in proper position certain connections in the dobby head of a dobby loom and more especially to the connections between the rocker arm and the jackknives in a dobby loom.

It is a well-known fact that in one type of dobby head the rocker arms have upwardly and downwardly extending arms which rocker arms are mounted on a shaft horizontally disposed and this shaft and rocker arms are oscillated by power from the loom to cause the upper and lower ends of the rocker arm disposed on opposed sides of the dobby head to move backward and forward and having a connection with each end of both the upper and lower jackknives for reciprocating the jackknives for engaging the jack hooks to operate the harness of the loom to raise and lower the same to form the pattern. It is a well known fact that in connections heretofore used between the rocker arms and the ends of the jackknives that a certain amount of wear and play has resulted which causes improper manipulation of the jackknives and it is an object of this invention to provide reenforcing means for the connections between the rocker arm and the end of the jackknives whereby more efficient operation can be effected.

Some of the objects of the invention having been stated, other objects will appear as the description proceeds when taken in connection with the accompanying drawing, in which—

Figure 1 is a side elevation of a portion of a dobby head showing my invention attached to one of the rocker arms;

Figure 2 is a top plan view of the connections between the rocker arm and the jackknife;

Figure 3 is a longitudinal sectional view taken along the line 3—3 in Figure 2;

Figure 4 is a transverse sectional view taken along the line 4—4 in Figure 1;

Figure 5 is a bottom plan view of one of the members forming a part of my invention;

Figure 6 is a side elevation of the other portion of my invention.

Referring more specifically to the drawing, the numeral 10 indicates one of the side frame portions of the dobby head which has conventional dobby fingers 11 therein for controlling conventional jack-hooks 12 and as is well known in the art, upper and lower jackknives 13 are provided, their ends moving in slots 14 disposed on opposite sides of the dobby head and being provided in frame members 10. On opposite sides of the dobby head suitable rocker arms 15 are provided, the lower portion of one of these rocker arms be-

ing shown in Figure 1, which rocker arms have suitable slots 16 therein in which a bolt 17 is adjustably mounted which bolt penetrates a member 18 slidably secured on connecting rod 19. The other end of the connecting rod is pierced by a bolt 20 which pivotally secures connecting rod 19 to forked lug 21, which lug is penetrated by the rounded end 22 of jackknife 13. The structure thus far described is conventional and on account of the loose connection between connecting rod 19 and forked lug 21 by means of bolts 20 there is a certain amount of side play allowed and after the connection between forked lug 21 the portion 22 of jackknife 13 has become worn it allows a certain amount of sidewise movement of member 21 and results in that end of the jackknife not traveling at the proper speed.

The conventional connecting rod also has threadably secured thereon nuts 25 and 26 for confining lug 18 on connecting rod 19.

In order to overcome the objections to the above described conventional mechanism, I provide a reenforcing and stabilizing arrangement for preventing undue play in the connections between the rocker arms 15 and the jackknives 13. I provide a mechanism which can be easily installed on connecting rod 19 without the necessity of disconnecting the connecting rod 19 from either the lug 18 or the lug 21 and without the necessity of disconnecting the lug 18 from rocker arm 15 or lug 21 from jackknife 13. For installation of connecting rod 19 between nuts 25 and the end of forked lug 21, I provide two members 30 and 31. Member 31 is shown more in detail in Figure 6 and has cylindrical projecting portion 32 having a bore longitudinally thereof with a slot 33 cut in one side thereof so the member 31 can be inserted on connecting rod 19 without the necessity of disconnecting said rod at either of its ends. This member 31 has vertically disposed portion 34 having an arcuate face adapted to fit against the arcuate end of the two portions of forked member 21. On the rear face of vertically disposed portion 34 is provided a cavity 35 for the reception of the unthreaded end of threaded screw 37 mounted in upstanding projection 38 on member 31.

This screw 37 has a portion 39 usually hexagonal and made integral with screw 37 by means of which the screw 37 can be turned. Screw 37 is threadably secured in a hole penetrating projection 38 and has a lock nut 40 thereon for securing the screw 37 in adjusted position. Member 30, as above stated, has upwardly projecting portion 38 which extends on down on opposite

sides of member 30 for strengthening the same and prevents its spreading apart, because member 30 has a slot 42 in the lower side thereof so that this too can be slipped over rod 19 when the parts 30 and 31 are turned to a position to cause slots 42 and 33 to coincide. Member 30 has a cavity 43 in one end thereof adapted to receive one face of nut 26. Member 30 has an enlarged longitudinally disposed cavity 44 into which projecting portion 32 of member 31 fits in a slidable manner. Member 30 is cut away as at 45 to allow room for screw 37 and lock nut 40.

In attaching members 30 and 31 to a connecting rod 19 all that is necessary is to loosen nuts 25 and 26 and to move portion 18 slightly to the left in the figures to allow room for insertion of members 30 and 31 on the rod 19, or if desired, screw 37 can be screwed down into projection 38 so as to allow barrel 32 of member 30 to be slipped further into cavity 42 of member 30, and member 31 has its barrel portion inserted in the cavity 44 of member 30 and slots 33 and 42 in the two members are placed in coinciding position and the members are slipped sidewise onto rod 19 and then the slot 33 in member 31 assumes a position where it opens laterally and member 30 is turned so the slot 42 is member 30 assumes a position where it opens downwardly and then nuts 25 and 26 are adjusted to the proper position and then screw 37 is turned to cause its right hand end in the drawing to enter cavity 35 and the arcuate face of member 31 occurring in portion 34 is pressed snugly against the arcuate end of the forked lug 21 in this position the parts are adjusted to form a rigid forcing mechanism for connecting rods 19. It is thus seen that screw 37 prevents relative turning movement between members 30 and 31.

In the drawing and specification, there has been set forth a preferred embodiment of the invention, and although specific terms are employed, they are used in a generic and descriptive sense only and not for purposes of limitation, the scope of the invention being set forth in the appended claims.

I claim:

1. In a dobby loom having rocker arms and

jackknives and having a connecting rod pivotally connected to the end of each rocker arm and the end of each jackknife, a reenforcing member comprising telescoping members having longitudinally disposed bores and having a slot in one side thereof permitting insertion of the telescoping members onto the connecting rod, said members being turnable with relation to each other and threaded means on one member for engaging the other member to spread said members apart from each other and to force the outer end of said members against portions of the connecting rod for reenforcing and stabilizing the same.

2. In a dobby head having rocker arms and jackknives and connecting rods disposed between the ends of the rocker arms and the ends of the jackknives, a reenforcing member comprising two members telescopically mounted with relation to each other having slots therein permitting insertion of said members onto said connecting rod, said members being rotatable with relation to each other and adjustable means on one member for engaging the other member for adjusting the overall space occupied by the two members.

3. In a dobby loom having a dobby head provided with rocker arms and jackknives and connecting rod pivotally connected to rocker arms and said jackknives, a reenforcing member insertable on said connecting rod without disconnecting said connecting rod from the rocker arms and jackknives, said member comprising two hollow members having slots in one side thereof for insertion onto the connecting rod, one of said hollow members being slidably mounted on the other hollow member and means for spreading the hollow members apart from each other.

4. A reenforcing device insertable on a rod and the like comprising two hollow members having slots in their side portions extending into the hollows in said members, said members being telescopically mounted and being rotatable with relation to each other and means for spreading said members apart on said rod.
